H. M. JOHNSON

APPARATUS FOR REAMING SMOKING PIPES

Filed Nov. 30, 1927

Inventor:
HAROLD M. JOHNSON,
By John N. Brumagh
His Attorney.

UNITED STATES PATENT OFFICE.

HAROLD M. JOHNSON, OF ST. LOUIS, MISSOURI.

APPARATUS FOR REAMING SMOKING PIPES.

Application filed November 30, 1927. Serial No. 236,639.

This invention pertains to reaming devices and more particularly to apparatus for reaming smoking pipes.

One of the objects of this invention is to 5 provide a device which may be installed in a convenient location, in a cigar store or similar place convenient to smokers, and which may be used to ream out the burnt incrustation in the bowl of a smoking pipe in a 10 convenient and simple manner.

Another object is to provide such a device, which may be easily and quickly adjusted to ream any size of pipe.

Another object is to provide such a device 15 which will not only ream the bowl, but by which a suitable chamfer may be applied to the upper edge of the bowl.

Another object is to provide such a reaming device in combination with a suitable re- 20 ceptacle for receiving the cuttings, so as to prevent their being scattered about the place.

Further objects will appear from the following description, taken in connection with the accompanying drawing, in which—

25 Figure 1 is a vertical section of a reaming device embodying this invention;

Figure 2 is a plan view of Figure 1, with the cover removed. In this figure, the shanks of the reamers are shown as cut off so as to 30 show the construction of other parts.

Figure 3 is a detail section on line 3—3 of Figure 1.

Referring to the accompanying drawing, 1 designates a bracket which may be arranged 35 for attachment to the wall, as indicated at 2, and which provides a support for the apparatus. Mounted on the support 1 is a vertical bearing 3, in which is mounted for rotation a vertical shaft 4. This shaft has fixed 40 to its lower end a bevel gear 5 meshing with a corresponding gear 6 on a cross shaft 7 journaled in the support 1. The shaft 7 has secured to the other end thereof an operating crank 8. By turning the crank 8, the shaft 45 4 may be driven through the agency of the gears 5 and 6.

The upper part of the support 1 is formed 50 to provide a housing 9. Within this housing there is fixed to the shaft 4 a gear 10. Loosely mounted on the shaft 4 and above the gear 10 is a turret 11. The turret 11 may be formed of sheet metal, as shown in the drawings. A hub 12 is fixed to the middle thereof, while at spaced points around its periphery the sheet is cut radially and portions thereof bent

downwardly to provide ears 13. The turret is held in place on the shaft 4 by a collar 14 secured by a set screw 15 or other suitable fastening.

Pivoted on screws 16 threaded into the ears 60 13, is a series of bearing blocks 17. The blocks 17 are spaced around the periphery of the turret 11 and are arranged to pivot on the screws 16 so that they may be turned to different positions thereon. Journaled in 65 each of the bearing blocks 17 is a reamer 18. Fixed to the shank of each reamer 18 is a pinion 19.

The housing 9 is provided at one point in its periphery with a gate or door 20. Within 70 this door-way, there is located in the bottom of the housing 9 a guide socket 21. The parts are so proportioned that the turret 11 may be turned upon the shaft 4 until a reamer 18 of the desired size is brought opposite the door 75 20. This reamer may then be swung downwardly through the door on the pivot screws 16 until its shank engages the socket 21. In this position the pinion 19 will establish driving connections with the gear 10. A keeper 80 22 is pivoted at 23 on the bottom of the housing 19 and is arranged to swing on said pivot, so as to engage the shank of the reamer 18 positioned in the socket 21. In this position, the keeper 22 completes the guide 21 so as to 85 form, in effect, a bearing for the reamer shank. The keeper 22 is held in place by a spring latch 24.

The support 1 extends downwardly and has formed or mounted thereon a bowl or receiver 90 25 adapted to receive the cuttings. A cover 26 may be provided for the housing 9 so as to enclose those reamers which are in idle position.

In the use of this device, the smoker selects 95 a reamer 18 of the proper size to fit his pipe, moves the turret 11 around so as to bring that reamer opposite the gate 20 and then swings the reamer downwardly from idle position to reaming position, with its cutting end extending downwardly and its shank engaged in the socket 21. During this movement, the reamer turns with the bearing block 17, which pivots on the screws 16. At the completion of the movement, the pinion 19 establishes driving 100 connections with the gear 10. The operator then swings the keeper 22 into position until it latches at the latch 24. By now operating the crank 8, the shaft 4 will be driven, as previously described, and will, in turn, through 110

the agency of the gear 10 and the pinion 19, drive the reamer. The operator now brings his pipe into engagement with the lower end of the reamer, which will operate to cut out the incrustation in the bowl to any extent desired. One of the reamers is provided with a chamfering head 27, so that when the reaming of the bowl is completed, this reamer may be brought into operative position and a suitable chamfer cut on the inner upper edge of the pipe bowl. The operator knocks out the cuttings from his pipe into the bowl 25.

It will be seen that this invention provides a simple and effective means for cleaning out smoking pipes. An assortment of reamers of various sizes to fit any size of pipe is mounted in the turret and ready to be swung to reaming position by a simple operation. When in that position, the reamer is securely locked and held in operative relation with the driving mechanism connected to the crank 8. The reaming takes place by a simple movement of the crank, while holding the pipe in engagement with the reamer. The bowl 25 provides a convenient receptacle for receiving the cuttings.

It is obvious that various changes may be made, within the scope of the appended claims, in details of construction without departing from the spirit of this invention. It is, therefore, to be understood that this invention is not limited to the specific details shown and described.

Having thus described the invention, what is claimed is:

1. An apparatus for reaming smoking pipes, comprising, a support, a series of reamers mounted on said support for movement to reaming position, a guide on said support adapted to receive a reamer when moved to reaming position, and means for driving the reamer in said guide.

2. An apparatus for reaming smoking pipes, comprising, a support, a series of reamers mounted on said support for movement to reaming position, a guide on said support adapted to receive a reamer when moved to reaming position, and means for driving the reamer in said guide adapted to establish driving connections therewith upon movement of the reamer to reaming position.

3. An apparatus for reaming smoking pipes, comprising, a support, a turret mounted for rotation on said support, a series of reamers mounted for movement on said turret to reaming and idle positions, a guide on said support adapted to receive a reamer when

moved to reaming position, and means for driving the reamer in said guide.

4. An apparatus for reaming smoking pipes, comprising, a support, a turret mounted for rotation on said support, a series of reamers mounted for movement on said turret to reaming and idle positions, a guide on said support adapted to receive a reamer when moved to reaming position, and means for driving the reamer in said guide adapted to establish driving connections therewith upon movement of the reamer to reaming position.

5. An apparatus for reaming smoking pipes, comprising, a support, a turret mounted for rotation on said support, a series of reamers pivotally journaled on said turret for movement to reaming and idle positions, a guide on said support adapted to receive a reamer when moved to reaming position, and means for driving the reamer in said guide.

6. An apparatus for reaming smoking pipes, comprising, a support, a shaft journaled in said support, a turret loosely mounted for rotation on said shaft, a gear fixed on said shaft, a series of reamers pivotally journaled on said turret for movement to reaming and idle positions, each of said reamers having a pinion thereon adapted to establish driving connections with said gear when in reaming position, and means for driving said shaft.

7. An apparatus for reaming smoking pipes, comprising, a support, a shaft journaled in said support, a turret loosely mounted for rotation on said shaft, a gear fixed on said shaft, a bearing block pivoted on said turret, a reamer journaled in said block and pivotally movable therewith to reaming and idle positions, a pinion on said reamer adapted to establish driving connections with said gear when in reaming position, and means for driving said shaft.

8. An apparatus for reaming smoking pipes, comprising, a support, a shaft journaled in said support, a turret loosely mounted for rotation on said shaft, a gear fixed on said shaft, a series of reamers pivotally journaled on said turret for movement to reaming and idle positions, each of said reamers having a pinion thereon adapted to establish driving connections with said gear when in reaming position, means for driving said shaft, and an enclosure for said turret.

In testimony whereof, I affix my signature this 22nd day of November, 1927.

HAROLD M. JOHNSON.
